TEXTIELMAATSCHAPPIJEN MAUTNER, OF ROTTERDAM, NETHERLANDS.

SHUTTLE-DRIVE ARRANGEMENT.

Application filed June 25, 1924. Serial No. 722,420.

To all whom it may concern:

Be it known that I, FERDINAND SOUCZEK, citizen of Czechoslovakia, residing at Nachod, Czechoslovakia, have invented certain new and useful Improvements in Shuttle-Drive Arrangements, of which the following is a specification.

This invention relates to loom picking mechanism of the kind in which continuously driven friction rollers are arranged in a race on both sides of the lay.

A preferred embodiment of the invention is shown on the drawing by way of example.

Figures 1-3 show an improved gripping roller in various elevations and sections.

Figure 4 shows the shuttle gripped by the gripping roller.

Figures 5-7 are diagrams illustrating the mode of action of the gripping roller and means for limiting the vertical movement of the shuttle.

Figures 8-10 illustrate an arrangement of shuttle box and an improved brake in three different positions and

Figure 11 illustrates an improved buffer.

The main differences between the improved gripping roller and the gripping roller heretofore proposed lies in the fact that the "wedge edges" of the roller instead

of being closed only at the moment when the shuttle is thrown are constantly closed being maintained in this position by resilient means and furthermore free entrance of the shuttle into the shuttle box is absolutely ensured by a lowering of the roller, i. e., by disappearance of the wedge edges from the race.

The improved roller has four instead of two wedge edges so that not only is the frictional work or efficiency of the gripping roller increased but the flexing of the side walls of the box is entirely prevented. For this purpose the shuttle 10 as shown in Fig.

4 is provided with two working bars 11 and 12 which are formed in the bottom of the shuttle without any alteration in the actual shape of the latter. When the bars 11, 12 become worn they may be made up to the right thickness again by gluing on veneer (ply-wood) or any other suitable ma-

terial or the bars themselves may be made of fibre fixed either directly or by gluing to the shuttles and this can be repeated as often as is necessary.

The improved gripping roller consists of two pairs of discs 1, 1 and 2, 2 loosely

mounted on the pulley hub 3 and driven by the carrier pins 4 without in any way reducing the lateral adjustability of the discs. The hub of the pulley 3 is rotatably mounted on ball bearings 6 on a spindle 5 and in addition to the holes for the carrier pins the belt pulley is also provided with a number of concentric axial holes for receiving a set of compression springs 7 and a set of tension springs 8. The compression and tension springs are symmetrically arranged and their object is to ensure an equal springing or compression on both sides of the pairs of discs 1, 1 and 2, 2. The discs 2, 2 in addition to the holes for the carrier pins are also provided with holes to receive the tension springs 8 which are held by pins 9. It is advisable to make the tensile power of the tension springs somewhat greater than that of the compression springs so that the outer discs 1, 2 will be pressed with certainty against the shoulder of the hub of the pulley 3 thus preventing the discs from being thrown sideways. This arrangement of springs passing right through the discs and pulley has the advantage that both pairs of gripping discs work with exactly the same force. It is however immaterial as regards the mode of action of the grip in what way the springs holding together the pairs of discs are arranged; thus for example instead of the spiral springs radial leaf springs engaging on the outer surface of each disc may be used or again the individual wedge discs may themselves act as springs if they are made of thin steel plate and of suitable diameter.

As will be seen from Fig. 4 the wedge edges of the pairs of discs are only forced apart to an inconsiderable extent by the shuttles and this only at the points of contact indicated at a Fig. 5 of the roller edge with the working rails 11 and 12 of the shuttle 10 the discs remaining closed at the diametrically opposite point to the point of contact. Owing to this the planes of the discs during operation of the gripping roller are oblique relatively to each other, as seen in Fig. 4, and therefore it is not sufficient for the discs to be merely loosely mounted on the hub as either the bore of the discs or the seating surface of the hub must be correspondingly bulged to prevent jamming.

The lift of the shuttle is limited by a plate 13. The latter, as will be seen from Fig. 5

is not arranged exactly vertically above the spindle 5 of the gripping roller as in the usual construction but is displaced slightly in the direction of "the pick" so that the line 5 of connection from the spindle 5 of the gripping roller and the point of contact of the lift limiting plate 13 forms an angle α with the vertical. Owing to this moreover the theoretical direction of pick is deviated 10 by this angle α from the horizontal. The shuttle race however prevents the shuttle from taking this direction which is indicated in Fig. 5 by $m-n$. The front tip of the shuttle owing to the endeavour of the shuttle 15 to follow the theoretical direction is pressed against the race while the rear end lifts away from the race. This ensures the smooth running down of the shuttle in the same way as has sought to be done in the 20 ordinary over pick loom by arranging the picker spindles higher up relatively to the lay. A further advantage of the present arrangement lies in the fact that the limiting bars 13 can be fitted higher thus giving 25 greater clearance between them and the entering shuttle.

A still greater clearance between the shuttle and the height limiting plate is secured by the arrangement shown in Figs. 6 30 and 7. In this embodiment the limiting plate 13 can rotate about the pivot pin 14 which is fixed to the arm 15. This arm 15 is capable of rocking in the direction of the arrow shown in Fig. 7 about a pivotal point 35 16 and is held by a stop and spring in the vertical position shown in Fig. 6 or even in front of the said position. If the shuttle is now brought within range to be acted on by the roller and consequently pressed 40 against the height limiting plate the latter is carried along by friction the arm 15 being rocked through the angle β from the position of rest. This angle of deviation is equal to the angle of friction so that the 45 tangent of angle β is equal to the coefficient of friction. As the latter depends on the material it follows that for any desired lateral displacement of the height of lift the length and position of the arm 15 can be determined. So soon as the shuttle has left 50 the rollers the arm of limiting plate returns to the original position and at the same time rises so that the vertical clearance can be still further increased. Owing to the possibility of rotation of the bar 13 round the pin 14 they are made to lie effectively 55 against the shuttle and it is therefore rendered possible to give them a very flat or straight form so as to produce a surface contact instead of a line contact.

For the purpose of raising and lowering the gripping roller it is mounted on a cranked lever 18 which can turn about a fixed spindle 17 Fig. 5. The other end of 60 this cranked lever is engaged by the tie rod

19 which in turn by simple lever transmission and cams is drawn downwards at the moment of picking the shuttle, owing to which the gripping roller is swung into the working position, in order, after the throw 70 of the shuttle to pass back into the position of rest which is shown on Fig. 5 by dotted lines.

By using a crank lever instead of a straight one the tie rod 19 is subjected to 75 hardly any strain because in the first place the line of pressure lying between the pivotal point of the gripping roller and the height limiting plate almost coincides with the pivotal point of the crank lever, and in 80 the second place the recoil produced in the gripping roller by the throw of the shuttle occasions a torque in the direction of the tensile stress (the tie rod.)

The brake action on the shuttle entering 85 the box differs from the known arrangement in the first place by the fact that the brake wedge is relieved by a kind of swinging gear. In the shuttle box are mounted two fixed spindles 21 and 22 Figs. 8-10 said 90 spindles carrying vertical and horizontal arms 23 and 24 respectively the arms being rotatable about the spindles and are provided with hook-shaped shoulders 25 and 26 for receiving swinging supports 27. 95 Around both the spindles mentioned a spiral spring is wound which tends to turn the arms in the direction shown by the arrow. Owing to this the swinging support 27 is held stationary in its position which is defined by the connecting line of the two shoulders 25 and 26 serving as the swinging support bearing with the spindle 21. Pressure exerted on the outer end of the arm 24 which is provided with a second swinging support bearing 28 is transmitted by the swinging support 27 direct to the spindle 21. If by downward movement of a lever 46 also mounted on the spindle 21 the arm 23 is swung to the left the swinging support 27 will be brought into the oblique position shown in Fig. 10 and the arm 24 will be inclined. In this movement the swinging support bearing 28 is lowered 100 to some extent. In this swinging bearing there rests a swinging support 30 carrying a brake block 29.

A further improvement resides in the fact that the shuttle to be braked does not 105 act directly on the spring 32 which absorbs its momentum but acts through a lever 31 to which a spring 32 is fastened at a point near to the pivot point of said lever 31 whereby said spring exerts a force proportional to the ratio of the length of the lever and the distance of the fastening of the spring from the pivot point. For this purpose the transmission lever (gearing down or purchase lever) is mounted in an arm 33 110 at the foot of the lay and is guided at its 115

upper end in guides 36 the movement being limited by stops 34 and 35. The transmission of the momentum of the shuttle to the lever 31 is effected by the buffer 38 which is 5 shown in plan view in Fig. 11 on an enlarged scale. The picker consists of a number of individual members 39 of leather or other suitable material joined to and connected with each other the end members 40 10 and 41 being of thick heavy leather the intermediate members between the end pieces expanding like a bellows. One end piece carries a leather loop 42 through which the spring controlled lever 31 is passed the other end piece being preferably made heavier and provided with a nick or groove 15 for the tip of the shuttle. The buffer is of medium length and if the shuttle strikes with great speed against it in the first place 20 only the small mass of the leather end piece 40 is compressed and thereafter the remaining part of the buffer, after which begins the momentum of the shuttle is transmitted to the lever 31 and spring 32. While the 25 sprung lever 31 is being moved outwards provision is made so that the brake block 29 is moved by a small force in the opposite direction and in this movement as it rests on the swinging support 30 is at the same 30 time moved upwards and thus gently presses the shuttle against brake bars 43 fitted on both internal sides of the shuttle box wall above the brake block opening. In the embodiment described this is obtained 35 by riveting a flat wire spring 44 to the swinging support 30 which spring is passed over a pin 45 of the lever 31.

As will be seen from Fig. 9 the brake 40 pressure is transmitted by the swinging support 30 to the ratchet gear. Owing to the fact that the lever 46 which releases the ratchet gear is connected by the spring 47 with the tie rod 19 when the latter is 45 operated not only is the gripping roller 1 brought by the crank lever 18 from its position of rest (Figs. 8 and 9) into the working position (Fig. 10) but at the same time the ratchet is moved to the position indicated in Fig. 10. Owing to this the brake 50 pressure is ended and the shuttle brought by the taut spring 32 within the range of

action of the gripping roller. The buffer owing to its mass inertia swings far beyond the position shown in Fig. 8 and is brought back to the latter by the elasticity of the 55 leather members.

I claim:

1. A loom picking mechanism having means for throwing a shuttle comprising friction rollers composed of wedge discs 60 and means for resiliently holding said discs together whereby a compacting pressure between the rollers and shuttle is obtained.

2. A loom picking mechanism having means for throwing a shuttle comprising friction rollers composed of wedge discs arranged in pairs, means for resiliently holding the outer discs of the rollers together and means for resiliently pressing the inner discs away from one another and 65 against the outer discs.

3. A loom picking mechanism having means for throwing a shuttle comprising friction rollers composed of wedge discs located at the ends of the lay and means 75 for raising the discs to engage the shuttle for the picking operation and thereafter lowering the discs out of the path of the shuttle.

4. A loom picking mechanism comprising means for throwing a shuttle and a height limiting plate for said shuttle capable of displacement slightly in the direction of the pick.

5. A loom picking mechanism comprising means for throwing a shuttle a height limiting plate for said shuttle which is displaced on the throw of the shuttle, a rocking arm carrying said plate and means for returning said plate to its initial position on the completion of the throw of the shuttle.

6. A loom picking mechanism comprising a shuttle, side walls on said shuttle the bottom portions of which are provided with longitudinally extending working bars having bevelled edges, and means for engaging the said edges for throwing the shuttle.

In testimony whereof I have signed my name to this specification.

FERDINAND SOUCZEK.
